UNITED STATES PATENT OFFICE.

EUGENE W. KING, OF SYRACUSE, NEW YORK, ASSIGNOR TO SEMET-SOLVAY COMPANY, OF SOLVAY, NEW YORK, A CORPORATION OF NEW YORK.

COKE OVEN.

Application filed December 29, 1921. Serial No. 525,569.

To all whom it may concern:

Be it known that I, EUGENE W. KING, a citizen of the United States, residing at Syracuse, in the county of Onondaga and 5 State of New York, have invented certain new and useful Improvements in Coke Ovens, of which the following is a specification.

My invention relates particularly to that 10 type or class of ovens known as "non-recovery" ovens in which the combustible gases generated in the ovens are not treated for the recovery of by-products but are taken directly to the heating flues and 15 burned therein to provide heat for the coking of the oven charge. Such ovens are employed in the coking of coal which is deficient in those elements which it is commercially worth while to recover as by-products. 20 The gas generated is consequently lean in quality and one of the objects of my improvements is to provide for the efficient utilization of this gas in heating the oven. To this end my invention consists in providing 25 means for the conservation of the heat of the gas as it comes from the ovens so that it is delivered to the heating flues and burned in a hot state and also in providing means for heating the air used to effect the 30 combustion of the gas. Another object of my improvements is to avoid the formation in the heating flues of deposits of the tar, pitch and other impurities with which the 35 gas coming from the ovens without cooling or scrubbing is charged.

The invention will be best understood by reference to the accompanying drawings, illustrating an embodiment thereof. Fig. 1 of which shows a vertical cross section of 40 an oven block, partly broken away to show the combustion flues, Fig. 2 shows a vertical section longitudinal of the oven block. Fig. 3 shows a section on the line 3—3, Fig. 4; Fig. 4, shows a section on the line 4—4, Fig. 45 Fig. 3; Fig. 3^b is a partial horizontal section showing the gas connections to the burners; and Fig. 5 is a section showing on an enlarged scale details of flue construction.

50 Referring to the drawings, A, A, indicate a series of coking ovens, forming a block of retort ovens, which are separated by division walls, B, B. Along the top of the block of ovens, longitudinal thereof, are 55 two gas collecting mains, C, C, each of which

is connected to each of the ovens, A, near the ends thereof by passages, D, D, through which the gases generated in the oven flow into the gas collecting mains. Between the gas mains C, are the usual charging orifices, 60 E, E, through which the coal charges are introduced into the oven. On each side of each of the ovens, A, and between the oven and the adjacent division wall, B, are heating or combustion, flues 1, 2, 3 which are arranged in two sets each extending half the length of the oven, and separated by a division wall, F, and connected by an upper flue, 4.

Below each oven are located two regenerators, G, H, which are respectively connected by ports, g, h, with sole flues, I, J. The sole flues I, J, are connected by ports, i, j, with the lowermost combustion flues 1, 1.

Between the regenerators, G, H, are 75 located flues, M, N, which run longitudinally of the oven block and are connected at the end thereof with a reversing valve, V, through which, alternately, air is admitted to the regenerators and the gases of combustion 80 flow to the stack.

From the gas collecting mains, C, C, narrow passages, K, K, formed in the division walls, B, B, lead downward and are connected by side passages, L, L, with the gas burner ports, k, k, of the combustion flues. The flow of gas to the gas burner ports is regulated by slide bricks, l, l, located in the passages, L, which are readily accessible 90 through ports, O, in the front and rear walls.

Since the gas from the collecting mains may be deficient in heating quality I have provided means consisting of gas supply pipes, P, extending along the sides of the 95 oven block and having branches, p, p, by which gas from a supplemental supply, as producer gas, can be led to the combustion flues. By this means the hot, raw gas from the collecting mains can be supplemented 100 with other or richer gas, or other gas can be substituted for the oven gas and the oven gas otherwise disposed of.

In the operation of the oven the gas driven off from the coal passes from the ovens by 105 passages, D, into the gas collecting mains, C, C, and thence directly downward by passages K, and side passages, L, to the burner ports, k, where it is met by the air for combustion. Since the gas passages, K, and side 110

passages, L, are located in the hot division walls between the ovens the gas loses practically no heat but is delivered at the burner ports at substantially the same temperature 5 at which it leaves the ovens and thus gives its maximum heating effect.

In case a cold supplemental gas is mixed with the oven gas at the combustion flues the combustion of this is also promoted by 10 the heat of the hot oven gas with which it is mixed.

The air for combustion, entering through one of the flues below the oven, as M, passes through and is heated in the regenerator, 15 G, and thence passes into the sole flue, I, and by port, i, to the lowermost combustion flue 1. Thence it passes upward through the several flues to flue, 4, by which it crosses to the uppermost flue, 3, of the 20 other set. The hot gases of combustion pass out from the lowermost flue by port, j, to sole flue, J, and thence to regenerator, H, and flue, N, by which they pass to the stack.

Upon reversal the air flows in the opposite direction, entering through the regenerator, H, and the products of combustion pass out through the regenerator G. In either case all the air required for the combustion of the gas is delivered at one end 30 of the series of combustion flues and hence is in excess until it reaches the last of the gas burners.

Thus any deposit of tar or pitch formed in the heating flues is burned out, first from 35 one end of the series of flues and then from the other, so that any accumulation thereof in the flues is prevented.

In the arrangement shown the gas collecting mains act as pressure equalizers for 40 the gas from the ovens so that gas is supplied to the oven burners at a uniform pressure and also serve to equalize the temperature of the gas so that there will be no local cooling of the gas, as upon charging an 45 oven. In case of excess of pressure in the collecting mains gas can be bled off to the air or transported for use elsewhere. By manipulation of the slide valves S, S, (Fig. 4) which control the passages K, D, 50 any individual oven can be cut out; as for repairs, without affecting the operation of those remaining in run.

Having thus described my invention what I claim as new and desire to secure by Letters Patent is:—

1. In a block of retort coke ovens, separated one from another by dividing walls, the combination of two sets of horizontally disposed heating flues, connected in series, 60 on each side of each oven, vertical gas passages located within the dividing walls and arranged to deliver gas from the ovens directly to one end of the heating flues of each set and regenerators located below and par-

allel with each oven and arranged to deliver 65 heated air alternately to the bottom flues of said sets of heating flues.

2. In a block of retort coke ovens, separated by dividing walls, the combination of two gas collecting mains running longitudinally of the block of ovens and arranged to receive gas from the ovens, two sets of horizontally disposed heating flues, connected in series, on each side of each oven, gas passages located within the dividing walls and arranged to deliver gas from the collecting mains to one end of the heating flues of each set and regenerators located below and parallel with each oven and arranged to deliver heated air alternately to the bottom flues of said sets of heating flues. 75

3. In a block of retort coke ovens separated from one another by dividing walls the combination of two sets of horizontally disposed heating flues, connected in series, 85 on each side of each oven, vertical gas passages located within the dividing walls and arranged to deliver gas from the ovens to one end of each set of heating flues, means for adding other gas to or substituting the same for the oven gas and regenerators located below and parallel with each oven and arranged to deliver heated air alternately to the bottom flues of said sets of heating flues. 90

4. In a block of retort coke ovens separated one from another by dividing walls the combination of two sets of horizontally disposed heating flues, connected in series, 95 on each side of each oven, vertical gas passages located within the dividing walls and arranged to deliver gas from the ovens to burners at one end of the heating flues of each set, means for cutting off or regulating the supply of gas at each of said burners and regenerators located below and parallel with each oven and arranged to deliver heated air alternately to the bottom flues of 100 said sets of flues. 105

5. In a block of retort coke ovens separated by dividing walls the combination of two gas collecting mains running longitudinally of the block of ovens and arranged to receive gas from the ovens, two sets of heating flues on each side of each oven, said two sets of flues being separated by a dividing wall and connected in series by a connecting flue, gas burners at one end of the flues of each set, gas passages located within the dividing walls between the ovens and arranged to deliver gas from said gas collecting mains to said burners and regenerators located below and parallel with each oven and arranged to deliver heated air alternately to the bottom flues of said sets of flues. 110 115

In testimony whereof I affix my signature. this 16th day of December, 1921.

EUGENE W. KING.
